LACE TABLE COVER

Howard Hooven, Doylestown, Pa., assignor to Quaker Lace Company, Philadelphia, Pa.

Application July 14, 1950, Serial No. 11,200

Term of patent 7 years

(Cl. D92—26)

To all whom it may concern:

Be it known that I, Howard Hooven, citizen of the United States of America, residing at Doylestown, in the county of Bucks and State of Pennsylvania, have invented a new, original, and ornamental Design for a Lace Table Cover, of which the following is a specification, reference being had to the accompanying drawing, forming a part thereof, in which the figure is a face view of slightly more than a quarter section of the lace table cover, showing my new design, the other three sections being identical with the quarter here disclosed, arranged in proper relation to complete the lace table cover. The section disclosed is shown over a dark background to bring out the details of the lace design.

I claim:

The ornamental design for a lace table cover, substantially as shown and described.

HOWARD HOOVEN.
